SCRUB BRUSH HANDLE ATTACHMENT

Anna W. Fry, St. Louis, Mo., assignor to Itsa
Manufacturing Co., a corporation of Missouri

Application August 23, 1948, Serial No. 45,721

2 Claims. (Cl. 306—17)

1

This invention relates generally to a device for attaching an elongated handle to a scrub brush, whereby the latter may be manipulated while the operator remains upright, and has for one of its objects the construction of such a device that will be quickly and easily adjustable to fit various widths and shapes of brushes found on the market, and so that said brush may be manipulated either longitudinally or transversely of itself over the work surface.

Another object of my invention is to so construct a device of the kind described, so that the elongated manipulating handle will cooperatively engage with the other parts of the device, to either adjustably lock the handle at predetermined angles relatively to the brush, or to freely swivel relatively of the latter throughout a full angular range of substantially 180°.

A further object of the invention is to so construct such a device that it will be extremely rigid and durable in service, and will not easily become bent or otherwise distorted and unusable.

An added object of the invention is to so shape and proportion the mating parts of the device, that one of said mating parts will be provided with a pair of spaced apart elements that will engage one side of the brush, while the other mating part will have but a single such element to engage the other and corresponding side of the brush and may be completely slid between said pair of spaced elements, to provide for clamping the device in place on brushes of various widths as will be found on the market.

The invention has among its other objects, to produce a device of the kind described, that will be relatively simple in construction and operation, have but a minimum number of parts, and which will be otherwise satisfactory and efficient of use wherever found applicable.

Many other objects and advantages of the construction herein shown and described, will be obvious to those skilled in the art to which this invention appertains, as will be apparent from the disclosures hereinafter given.

To this end, my invention consists in the novel construction, arrangement, combination, and form of parts herein shown and described, and uses mentioned, as will be more clearly pointed out in the following specifications.

In the drawings, wherein like reference characters represent like or corresponding parts throughout the views,

Figure 1 is a perspective view of the device clamped ready for use, on a scrubbing brush;

Figure 2 is a top plan view of the pair of mat-

2

ing members of the clamp, in approximately their operative relationship when on the brush, but with the brush, adjustment means and the handle omitted for the sake of clearness;

Figure 3 is a transverse cross-sectional view of the parts shown in Fig. 1, through the transverse median line of the latter; and

Figure 4 is an end view of the same, with the handle rotated a half-turn on its longitudinal axis, to its freely pivoting position relatively to the pair of clamp members.

Referring more particularly to the drawings, wherein I have illustrated my preferred form of clamp for attaching a manipulating handle to a scrub brush, I indicates the body or back of a scrub brush of usual or special construction, having the pair of spaced sides 2—2 extending lengthwise of the brush and with finger grooves or channels 3—3 extending therealong somewhat as indicated, and with the pair of spaced transversely extending sides 4—4. Such brushes may be made of any suitable kind of material, as of wood, and provided with groups of tufts or bristles 5 mounted in place to project away from said body.

Usually such a brush is grasped with one hand and then manipulated across the surface to be cleaned therewith, but in order to make such work easier, and to do it while remaining more or less upright, I have arranged an elongated handle 6 for securement at one end to said brush, making the connection between the handle and brush such that the handle is conveniently adjustable to accommodate the many angles that are apt to be encountered with respect to the brush and the floor or other surfaces that are to be cleaned.

A pair of clamping members 7 and 8 are provided for mounting on the back or body of the brush, these clamping members being adjustably held together by a means that will soon be more clearly described, such means also providing a pivotal axis for the operating handle, as will also be seen.

It is essential that each of said clamping members be sturdy and rigid, this being had by casting or otherwise suitably forming the same of the required strength, as it has been found that when the device is of weaker construction, as for example when formed of sheet metal, it is too flexible to withstand the normal strains of use, with the result that the device would be too short-lived to be popular, and would become distorted and cause trouble in operation of the various parts.

To prevent such possible source of trouble, the members 7 and 8 are preferably made rigid as aforesaid, the former being formed to provide a pair of spaced apart legs 9—9 to extend transversely across the back of the brush, as indicated in Figs. 1 and 3, each of said legs provided with an angularly disposed portion, such as the downwardly extending claw, jaw or leg 10, at one end of the leg 9 so as to overlie the side of the brush back, said element 10 being shaped to provide a terminal tooth or rib 11 that is adapted to engage in the adjacent finger groove of the brush body.

A flange 12 extends upwardly from said pair of legs 9—9 in a direction substantially lengthwise of the brush, to bridge between said pair of legs, the portion of the flange that is between said pair of legs being undercut or provided with a vertical clearance 13 therebelow to permit free passage of the top leg of the mating clamp member 8 thereunder, as will presently be set forth.

The other member 8 of the pair of clamping members is formed with but a single transverse leg 14 to be superimposed on top of the brush back, and at one end of said leg there is an angularly directed claw or leg 15, provided with a tooth or rib 16 arranged to lie within the finger groove that is provided adjacent that side of the brush body.

Said member 8 is further provided with an upstanding flange 17 that extends longitudinally of the brush back to oppose the corresponding flange 12 of the mating member 7 when both members are in their assembled relationship as indicated in the drawings, one end of the leg 14 fitting between the pair of spaced apart legs 9—9 and slidably passing beneath the flange 12 in the vertical clearance 13 provided thereat.

It is to be particularly noted that each upright flange 12 and 17 respectively, is spaced intermediate the ends of the legs to which they are attached and are part, and have a thickened cross-section along their base. This greatly increases the strength of said flanges and resists the tendency to bend when the mating parts are clamped onto the brush. The portions of said legs have sufficient bearing on the brush body, on both sides of the flanges, to absorb the strain.

The construction aforesaid, of one of the mating clamps being sufficiently narrow to wholly slide between the pair of legs of the other member, will prevent longitudinal displacement of the members relatively of one another, and as one leg is beneath the flange of the other member, any undue lifting of such leg is prevented.

Both of said upright flanges are provided with bores therethrough, to receive the tightening bolt 18 therethrough, one end of the bolt receiving a washer 19 and wingnut 20 thereon.

A T-shaped ferrule or sleeve consisting of the cylindrical barrel 21 to engage between the opposed faces of the pair of flanges and receive the fastening bolt 18 therethrough, is arranged to pivot about said bolt as an axis, the offset portion 22 of said ferrule arranged to receive one end of the handle 6, so that the latter extends closely adjacent the bottom of said barrel 21, and is then drilled out in registry with the bores through the flanges, and thereby prevent the handle pulling out when the bolt is inserted therethrough.

In order to lock the handle in place at any one of a series of predetermined angular positions relatively of the brush, pin and detent means may be provided at one side of the barrel

portion of the ferrule, as by a series of pins 23 spaced circumferentially about the inside of the flange 12, and the series of detents or recesses 24 similarly arranged and opening onto the flat face of said ferrule opposed to said flange, and adapted to receive said pins, as indicated in Fig. 3. Obviously, the handle may be adjustably set at any angular relationship to the brush in this manner.

However, it is sometimes deemed advisable to use the brush with a freely pivoted handle; hence for such use, the handle is detached from its limited pivotal interlock, rotated a half-turn or about 180° on its longitudinal axis, and then retightened in place as indicated in Fig. 4, whereupon the pins act as bearing points to permit ready pivotal movement of the handle through the full swing of approximately 180°.

Having thus described my invention, it is obvious that various immaterial modifications may be made in the same without departing from the spirit of my invention; hence I do not wish to be understood as limiting myself to the exact form, arrangement, combination and construction of the parts herein shown and described, or the uses mentioned, except as limited by the state of the art to which this invention appertains, and the claims hereunto appended.

What I claim as new and desire to secure by Letters Patent is:

1. In an attachment for a brush, a pair of clamp members adjustably mountable on a brush back to pivotally receive an operating handle, one of said clamp members having a pair of spaced brush-back engaging top legs to extend transversely across the top face of said brush back and provided with claws at one end to engage the side of said brush back and an upright flange intermediate the opposite ends of said top legs bridging the space between said top legs, the other clamp member having a brush-back engaging top leg to be superimposed transversely of the top of said brush back and provided with a downwardly extending claw at one end to engage the side of said brush back, the top leg of said second clamp member being of a size to slide between said pair of legs of said first clamp member and to pass beneath said upright flange of the latter, the brush-back engaging faces of all of said top legs lying in a common plane, an upright flange intermediate the ends of the top leg of said second clamp member to oppose the corresponding flange of the first clamp member when said pair of clamp members are mounted in operative position on said brush back, and means for adjustably interconnecting said flanges to actuate said clamp members together and provide a pivotal connection for an operating handle.

2. In an attachment for a brush, a pair of clamp members adjustably mountable on a brush back to together pivotally receive an operating handle therebetween, one of said members having a pair of spaced apart substantially horizontal legs to extend transversely across and engage said brush back and provided with downwardly directed claws at one end to engage the side of said brush back and an upright flange intermediate the ends of said top legs bridging the space between said top legs, the other clamp member having a substantially horizontal top leg to be superimposed transversely of and engage the top of said brush back and provided with a downwardly directed claw at one end to engage the side of the brush back, the leg of said second member being of a size to freely slide between

the spaced apart pair of legs of the first member past the free ends of said spaced apart legs and to pass beneath the upright flange of said first member, all of said brush-back engaging faces lying substantially in a common plane, an upright flange intermediate the ends of the top leg of said second member, and means for adjustably interconnecting said upright flanges of both members for clamping said members together onto said brush back and providing a handle connection pivotally engaging both of said upright flanges.
